UNITED STATES PATENT OFFICE.

EDWARD F. SEERY, OF PROVIDENCE, RHODE ISLAND.

DESIGN FOR AN ORNAMENTAL CHAIN-LINK.

SPECIFICATION forming part of Design No. 12,653, dated January 3, 1882.

Application filed November 11, 1881. Term of patent 7 years.

To all whom it may concern:

Be it known that I, EDWARD F. SEERY, of the city and county of Providence, State of Rhode Island, have invented and produced a new and original Design for Ornamental Chain-Links, of which the following is a full, clear, and exact description, reference being had to the accompanying drawings, forming part of this specification.

10 The leading feature of my design consists in a raised, plain, or ornamented surface formed in the center of the tapering sleeve of an ornamental chain-link.

15 Figure 1 is a view of a chain-link provided with a tapering sleeve, *a*, and a raised surface, *b*, formed on the center or largest part of the sleeve. Fig. 2 is a view of an ornamental chain-link provided with a sleeve tapering from the center toward both ends, on which a raised 20 and ornamented surface is formed in the center and a raised ring or surface on each end. Fig. 3 is a view of an ornamental chain-link provided with a sleeve tapering from the center to both ends. A raised ornamented surface 25 is formed in the center and rounded beads or rings are formed on the ends of the sleeve.

In the drawings, *a a a* are the sleeves, made tapering from the center toward the ends. In

these sleeves the connecting-loops are secured, as is shown in the drawings.

b is a central raised, flat, or ornamented surface, which may be formed of the metal of the sleeve. It may therefore be of the same color as the sleeve or of any other color.

c c are raised rings or surfaces at the small 35 ends of the sleeve, which may be formed of the metal of the sleeve.

The sleeves *a a* may be made round, square, six or eight sided, or oval.

Heretofore ornamental chain-links have been 40 made in which sleeves of uniform diameter have been used ornamented by engraving, cutting, and slotting.

Having thus described my newly-invented design, I claim as new and desire to secure by 45 Letters Patent—

The design for ornamental chain-links herein shown and described, the same consisting of a sleeve tapering toward both ends and provided with a raised surface in the center of the sleeve, 50 as described.

EDWARD F. SEERY.
